UNITED STATES PATENT OFFICE

2,597,536

LIQUID MIXER

Samuel Shields, Racine, Wis.

Application June 8, 1949, Serial No. 97,727

1. Claim. (Cl. 259—75)

1

My invention refers to oscillating liquid mixing machines, and it is particularly applicable to drink mixers.

The primary object of my invention is to provide a simple and effective actuating mechanism for oscillating the liquid container, whereby the usual vibrations developed in machines of this character are eliminated, resulting in silence of the parts, due to the specific structural features employed. In other words, the machine in its movements constitutes an anti-vibration device.

A further object of my invention is to provide an electric motor drive for the actuating mechanism under control of a standard "time switch," such as disclosed by U. S. Patents Number 1,353,850 and Number 1,773,697, whereby the actuating mechanism is driven for a pre-determined interval of time and thereafter automatically cut off, or the switch may be manually controlled to stop the motor at any point intermediate of the pre-determined interval of its travel by a main button and an auxiliary button.

A still further object of my invention is to provide a motor driven fly wheel having a true circular cam channel therein, the circular channel being slightly off center from the fly wheel center, whereby a rocking arm that engages the cam channel will impart oscillation to a master lever carrying the liquid container, it being understood that the container will oscillate back and forth once in each cycle of the fly wheel.

A further object of my invention is to provide a container having a slip cover, the said container being held in its nested position, relative to the master lever, by a latch, which latch is carried by a yoke for locking and releasing the said container from the yoke.

With the above and other objects in view, which will appear as the description proceeds, the invention resides in the novel construction, combination and arrangement of parts, substantially as hereinafter described, and more particularly defined by the appended claim, it being understood that such changes in the precise embodiment of the herein disclosed invention may be made as come within the scope of the claim.

In the accompanying drawings is illustrated one complete example of the physical embodiment of the present invention constructed according to the best mode so far devised for the practical application of the principles thereof.

In the drawings:

Figure 1 represents a sectional elevation of a machine embodying the features of my invention, the section being indicated by line 1—1 of Figure 3.

2

Figure 2 is a plan sectional view of the same, the section being indicated by line 2—2 of Figure 1.

Figure 3 is a longitudinal sectional view 5 through the machine, the section being indicated by line 3—3 of Figure 1.

Figure 4 is a detailed face view of a driven fly wheel and associated parts, the section being indicated by line 4—4 of Figure 2.

10 Figure 5 is a cross section of the same, the section being indicated by line 5—5 of Figure 4; and

Figure 6 is a fragmentary front view of the machine housing, illustrating the time switch in dotted lines, with its main button and auxiliary button extending through slots of the housing.

Referring by characters to the drawings, 1 indicates a base having upwardly extended legs 2 connected by a brace-bar 3.

The bar 3 has secured thereto a standard electric motor 4 carrying a back gear housing 4', and extending from which back gear housing is a drive shaft 5 that carries a V-shaped pulley 6.

Secured to the upper face of the frame strap 3 is a block 7, which block has shrunk therein a 25 pair of aligned bearings 8, 8 and an offset bearing 9, which offset bearing has journaled therein a stud shaft 10. The shaft 10 has secured thereto a fly wheel 11, provided with a peripheral belt groove, for the reception of an endless belt 12, which belt connects the fly wheel and the back gear pulley 6, whereby said fly wheel is driven.

As indicated in Figures 1, 4 and 5, the inner face of the fly wheel 11 is formed with a circular cam channel 12', the center of which channel is slightly offset from the center of the fly wheel.

The block 7 has journaled therein a rock shaft 13, one end of which has secured thereto a rocker arm 14, while the opposite end of said rock shaft 13 has secured thereto a segmental sector or 40 toothed arm 15.

Journalized in one of the bearings 8 of the block is a short shaft 16, which short shaft at each end projects beyond the block 7. One end of the short shaft 16 carries a tooth pinion 17, which 45 pinion meshes with the teeth of the arm 15, as best shown in Figures 1 and 3 of the drawings.

The opposite end of the short shaft 16 has secured thereto a master lever 18, and the outer end of said master lever has secured thereto a 50 transversely disposed yoke 19, having vertically disposed arms 19', 19'', the yoke intermediate of said arms being provided with parallel saddle straps 20. The master lever yoke 19 has nested therein a cylindrical liquid container 21, which container, at one end, is provided with a mouth and slip cover 21'. The slip cover carriage the

usual liquid agitator fork 22, and the cover and bottom of said container is provided with centrally disposed depressed cups 23, 23'. When it is desired to secure the container to the master yoke, it is dropped upon the saddles 20 of the yoke, and the cup 23' of the bottom end of said container engages a pin 24 carried by the yoke arm 19'. The cup portion 23' of said container cover is also engaged by a pin 24', which pin is carried by a spring controlled clip 25. The clip 25 is pivoted to the yoke arm 19'' and its bottom apertured end is mounted about a stud 25', between which clip bottom end and the yoke arm 19'' there is interposed a coil spring, whereby the clip pin 24' is held in its seat with relation to the cup cover 21'.

Hence, to remove or seat the container, it is only necessary to manually manipulate the spring controlled clip 25, whereby the container is removed or it may be firmly seated in the yoke.

Fitted over the entire mechanism is a housing 26, which is seated upon the base 1, and the upper end of the housing is provided with a slot 26' therein, through which slot the master lever extends, whereby the same, with its yoke and container are exposed.

The front wall of the housing has secured thereto a standard time switch A, carrying the usual main button *a*, and an auxiliary button *b*, which buttons project through slots in their housing wall, whereby they may be conveniently manipulated. An electric current is introduced through the housing 26 by a cable *c*, having supply wires *d* and *e*, which are suitably connected to the time switch buttons *a* and *b*, and said wires are also connected to the motor. For example, should it be desired to oscillate or mix the container fluid for 15 seconds, the time switch would be so set by manipulating the button *a*, whereby the motor is energized, and through its connections to the actuating mechanism, the container will be oscillated back and forth for 15 seconds, after which period the mechanism of the switch, not shown, will automatically break the electric circuit.

While I have illustrated the anti-vibrating mechanism specifically arranged to operate a

fluid mixer, it is understood that said mechanism may be utilized for various different purposes, and it is apparent, while I have shown the device applicable to a drink mixer, the same may be used for mixing any type of fluids, such as oil, paint, or the like.

It should also be noted that the rocker arm 14 carries an anti-friction roller 14', which roller enters the cam channel 12', whereby the master lever is oscillated once back and forth in one revolution of the fly wheel.

I claim:

In a device for mixing liquids, a support, a motor on the support, a horizontally disposed drive shaft rotatably mounted on the support, a fly wheel secured to the drive shaft for rotation therewith having a cam groove eccentric to the axis thereof, means including a pulley belt fitted over the outer periphery of the fly wheel for rotating the drive shaft from the motor, a horizontally disposed cross shaft rotatably mounted on the support at one side of the drive shaft, a crank arm secured to one end of the cross shaft having means engaging the walls of the cam groove, a toothed vertically extending sector arm secured to the other end of the cross shaft, a horizontally disposed rock shaft carried by the support disposed above the cross shaft, a pinion secured to one end of the rock shaft meshing with the teeth of the sector arm, and a work carrying vertically disposed rock arm secured to the other end of the rock shaft.

SAMUEL SHIELDS.
